COVER FOR KEGS, BARRELS, OR LIKE CONTAINERS

Robert G. Fessenden, Townsend, Mass.

Application April 23, 1935, Serial No. 17,774

1 Claim. (Cl. 217—76)

This invention relates to heads for kegs, barrels and other like wooden containers, and consists in improvements designed to simplify and strengthen the construction of such articles.

5 The invention has particular application to kegs, barrels and the like employed for the transportation and storage of liquids, semi-liquids or dry products where it is required that the head should effectively and securely close the top of

10 the container.

One object of the invention, among others, is to provide a head or cover which will permit its quick and ready application and its easy subsequent removal but will provide a permanently 15 tight joint, while securely held against displacement under pressure from within as well as from without. The described construction provides a readiness of application and removal for the head or cover and a security against displacement when 20 in place, not attainable with the type of head which is held in place by the usual croze or groove.

The invention will be best understood by reference to the following description when taken in 25 connection with the accompanying illustration showing one specific embodiment thereof, while its scope will be more particularly pointed out in the appended claim.

In the drawing:

30 Fig. 1 is a plan view of the open top of a keg embodying one form of the invention;

Fig. 2 is a side elevation of the keg shown in Fig. 1, the upper part being shown in cross-section;

35 Fig. 3 is a plan view of the top or cover;

Fig. 4 is a side elevation of the same;

Fig. 5 is a plan view of the removable binding or clamping hoop;

Fig. 6 is a cross-sectional elevation of the same;

40 Fig. 7 is an enlarged, cross-sectional view of the edge of the cover seated in the top of the keg before the clamping hoop has been applied thereto; and

45 Fig. 8 is a similar view after the application of the clamping hoop.

Referring to the drawing, the container 11, for 50 illustrative purposes, is shown in the form of a keg formed of wooden staves, the sides of which may be united either through plain joints or (as herein shown in Fig. 1) through a tongue and groove joint. The keg has a closed bottom which is not shown but which may be held in place by the usual groove or croze, or in any other desired manner, and the staves may be held together at

or near their mid portions by one or more bands 13 as indicated in Fig. 2.

The inner walls of the container near the open top thereof, instead of having formed therein the usual croze or groove, are cut back to provide 5 a preferably flat or square shoulder 15 extending circumferentially around the inside of the keg. This provides at the same time an enlarged, open mouth having the side walls 17 extending from the shoulder to the open top of the keg. These 10 side walls are preferably cut substantially parallel to the outside walls of the staves. Where, as in the illustrated form of container, the upper ends of the staves have a very slight inward inclination, the side walls of the enlarged mouth have a 15 similar slight inward inclination.

The removable top or cover 19 (Figs. 3 and 4) is disk-like in shape but is provided with tapered or beveled side walls, the bottom being of greater diameter than the top, and the whole forming 20 a truncated cone of large diameter and low height. The top is provided with means which may be gripped by the hands and pulled to remove the cover, such means being in the form of a screw-eye or ring 21.

25 When it is required to apply the cover to the keg, it is inserted in the open mouth of the keg in some such relationship as is indicated in Fig. 7, the flat peripheral edge of the underside of the cover resting on and abutting against the flat 30 face of the shoulder 15 formed on the inside of the staves. The ends of the staves, being then unconfined by any outside compression, present an enlarged mouth of such size as readily to permit the insertion of the cover, leaving a certain 35 amount of clearance between the walls 17 of the staves and the tapered side walls of the cover or head.

With this relationship of the head and keg, there is then applied a compressing band 23 (Figs. 40 5 and 6) to the ends of the staves which encircle the cover. This comprises an annular metallic band having sides which taper inwardly and upwardly from the bottom edge, the top edge terminating in a bead 25. The diameter of this 45 band is such that its bottom passes freely over the outside top edge of the keg, force being required to further depress it. When the band is thus applied to the keg, it is then forced down, as by hammering down on the bead 25, until it 50 assumes some such position as is illustrated in Fig. 8.

In the process of forcing down the band the ends of the staves are wedged inwardly and compressed edgewise together, contracting the 55

mouth of the keg about the side walls of the cover and bringing the parts into some such relationship as is shown in Fig. 8.

Preferably the relationship of the parts is such

5 that in the contraction of the walls of the keg under the compression of the band, the side walls 17 first encounter the beveled lower edge of the cover. Succeeding contraction, as the compressing band is forced further down, wedges 10 the upper parts of the staves inwardly, with the beveled cover edge serving as a fulcrum, until the side walls 17 for substantially their entire area are forced into close contact with the sides of the cover.

15 The result is that not only is there produced an effectively tight joint at the beveled edge of the cover, but the walls 17 of the staves wedged over and against the tapered walls of the cover force the bottom of the latter firmly and closely down 20 against the seat 15 and hold it immovable thereon in a position to resist any displacement by pressure from within. The facility with which this cover may be applied greatly speeds up the packing of all commodities in kegs and barrels.

25 Although the cover when thus applied is held securely fixed against all possible displacement occurring in transportation or storage, when desired, the cover may be readily and easily removed without breakage or damage thereto. Its removal merely requires the forcing upwardly of 30 the compressing band, as through the use of a hammer or other tool. As soon as the band is loosened it may be withdrawn and the cover readily lifted by the hand grip 21 and removed

unbroken from the keg. Since the cover may be thus removed intact and undamaged, it may be again reapplied at any time as previously described.

While I have herein shown and described for 5 purposes of illustration one specific embodiment of the invention, it is to be understood that extensive changes and modifications may be made in the details of the form by which it is herein illustrated, all without departing from the spirit 10 thereof.

I claim:

A keg or the like formed of wooden staves having a flat, open, seating shoulder around the inner periphery of the container near the end thereof 15 and presenting above said shoulder an enlarged open mouth of greater diameter than the shoulder with its inner walls substantially parallel to the outer walls of the staves, a cover having a flat peripheral bottom edge and inwardly and upwardly tapered side walls and of a diameter such that it may be readily entered into the open mouth of the container to be loosely seated on said seating shoulder, and a compressing band having also inwardly and upwardly tapering side walls adapt- 20 ed to encircle the end of said container and when forced downwardly thereover to force inwardly the inner walls of the staves first against the flat bottom edge of the cover to lock the latter to its seat the said flat bottom edge being so related 25 to the seating shoulder as to serve as a fulcrum about which subsequent movement of the staves takes place.

ROBERT G. FESSENDEN.
